UNITED STATES PATENT OFFICE.

ALBERT B. HERRICK, OF RIDGEWOOD, NEW JERSEY.

DESIGN FOR AN ELECTRIC SWITCH-JAW.

SPECIFICATION forming part of Design No. 30,152, dated February 7, 1899.

Application filed November 18, 1898. Serial No. 696,829. Term of patent 7 years.

To all whom it may concern:

Be it known that I, ALBERT B. HERRICK, a citizen of the United States, residing at Ridgewood, in the county of Bergen and State of New Jersey, have invented and produced a certain new and useful Design for an Electric Switch-Jaw, of which the following is a full, clear, and exact specification.

My design relates to electric switch-jaws; and its object is to produce a switch-jaw of serviceable and useful shape and design.

The design will be more fully described with reference to the accompanying drawings, in which I have illustrated a switch-jaw embodying my design, and in which—

Figure 1 is a perspective view of the jaw; Fig. 2, a side view of Fig. 1, and Fig. 3 an end view of the same.

As shown in the drawings, the leading feature of the design consists of the two straight portions *b* of the jaw, rectangular in cross-section, joined together by the compound curved portion *a*, of similar cross-section, the two straight portions and the curved portion all being a continuation of the same plane.

c represents the base, upon which the jaw is mounted, the jaw extending upward from the base, as is shown in the drawings.

The jaw therefore will comprise a continuous rectangular piece having the straight portions *b* extending upward from the base *c* in parallel directions and in parallel, but different, planes and joined together by a compound curve or bend *a*, the surfaces of the opposite sides of the jaw being parallel to each other throughout its length.

Having thus described my invention, what I claim as new, and desire to secure by Letters Patent, is—

The design for an electric switch-jaw, as herein shown and described.

In testimony whereof I affix my signature in presence of two witnesses.

ALBERT B. HERRICK.
